US00D615077S

(12) **United States Design Patent**
Richardson et al.

(10) **Patent No.:** **US D615,077 S**
(45) **Date of Patent:** **** May 4, 2010**

(54) **CASE**

(75) Inventors: **Curtis R. Richardson**, Fort Collins, CO (US); **John H. Loudenslager**, Phoenix, AZ (US); **Jamie L. Johnson**, Fort Collins, CO (US); **W. Travis Smith**, Fort Collins, CO (US); **Alan V. Morine**, Fort Collins, CO (US)

(73) Assignee: **Otter Products, LLC**, Fort Collins, CO (US)

(**) Term: **14 Years**

(21) Appl. No.: **29/344,271**

(22) Filed: **Sep. 25, 2009**

(51) **LOC (9) Cl.** **14-03**

(52) **U.S. Cl.** **D14/250**

(58) **Field of Classification Search** **D14/140, D14/142, 167, 217, 218, 240, 242, 248, 250–253, D14/299, 341–347, 440; D3/200–201, 215, D3/218–219, 226, 228, 269, 301, 272–273, D3/276, 294; D13/103, 107–108, 119; 220/4.02; 224/191, 240, 241, 245, 682–683; 248/206.2–206.4, 248/220.21, 279.1, 309.1; 361/679.3, 679.56; 379/420.04, 426, 433.11, 446–447, 454, 379/455; 455/575.1, 575.6, 575.7, 575.8, 455/575.9; 190/100; 206/305, 320**
